AUTOMATIC BIAS CIRCUITS

Hampton Jennings Dailey, Bloomfield, N. J., assignor to Westinghouse Electric & Manufacturing Company, East Pittsburgh, Pa., a corporation of Pennsylvania

Application May 29, 1941, Serial No. 395,803

1 Claim. (Cl. 250—36)

This invention relates to protective systems and methods and, more particularly, to thermionic valve circuits utilized in the generation or transmission of energy wherein in the absence of certain operating requirements damage may result to the valves.

The primary object of this invention is to prevent in the absence of certain operating conditions the deleterious effect which may be produced upon electron discharge devices and to this end means are provided for applying automatically bias potentials which establish static conditions in accordance with the characteristics specified for such devices.

A particular feature of this invention is that to protect electron discharge devices a safety bias potential is at all times applied to the circuit, although effectively it is counteracted by another potential which is derived from the transmission or signal currents present in the system. Consequently, if there are no transmission or signal currents in the system due to any cause whatsoever, the counteracting voltage will be zero and the safety bias voltage becomes automatically effective in the circuit.

Another feature of this invention is that the circuit arrangement whereby the bias voltage is applied and then counteracted requires no switching mechanisms or relays of any kind and is not dependent on mechanical safety devices heretofore used. Furthermore, the balance of potentials between the safety bias and the derived counterbias is such that partial failure of the latter will allow a proportional effective application of the former. Hence, the transitory stage between one and the other condition is gradual and smooth, permitting a balanced condition of operation of the electron tubes.

Other features and advantages will be apparent from the following description of the invention, pointed out in particularly by the appended claim, and taken in connection with the accompanying drawing, in which:

Figure 1 illustrates the protective circuit applied to a push-pull oscillator stage; and

Fig. 2 is a modification thereof applied to an amplifier stage.

Referring to Fig. 1, the protective system in accordance with this invention is shown being applied to a push-pull oscillator stage having a tuned input and a tuned output circuit. The former is a divided circuit comprising the center tapped inductance 1 paralleled by the tuning capacitor 2. One half of the inductance between center tap and one terminal is connected by

means of conductor 3 to the grid 4 of vacuum tube 5, whereas the other half through conductor 6 to the grid 7 of vacuum tube 8. The direct-current return path of the input circuit is completed from the center tap of the inductance 1 to the grounded cathodes 9 and 10 through a series network, including resistances 11 and 12, and a fixed voltage source represented by the battery 13. A shunt path around the resistors and the battery aforementioned may be effected by a switch 14 which when closed, shunts the contacts 15 and 16 and thereby returns the mid tap connection of the inductance 1 directly to ground. Under normal operation, as will be described later, the switch 14 is maintained open so that the grid return path is effected through the resistors 11 and 12.

The output circuit of the oscillator includes the output transformer 20, of which the primary 20 winding 21 is tuned by the condenser 22 and is divided by a center tap forming the anode return circuit through the anode supply source shown here by the battery 23. The anode 24 of tube 5 and the anode 25 of tube 8 are connected, respectively, to the free terminals of the primary winding 21. The output voltage of the oscillator may be taken off from the secondary winding 26 of the output transformer 20.

The above circuit follows the established practice of push-pull oscillators except for the addition of the bias source 13 and the resistor 12 which are part of the control circuit about to be described. The output transformer in the embodiment illustrated in Fig. 1 includes a tertiary winding 30 across which a certain output voltage will be developed when the oscillator is in normal operation. The winding 30 is connected in series with a rectifier, shown here as a two-element vacuum tube 31, to the resistor 12 which is shunted by a capacity 32.

In order to simplify the illustration, the filament heater connections of the vacuum tubes have been omitted in both figures. It is well known to any one skilled in the art that the required heater current may be obtained in any desired manner either from batteries or from alternating current power supplies. Similarly, certain voltage sources are represented by batteries merely for the convenience of illustration and may be substituted by other suitable sources operating from a power line circuit.

Before describing the operation of the protective circuit of Fig. 1, a description of Fig. 2 may be in order, since essentially the operation in both circuits is similar, except for certain circuit mod-

ifications for instance the coupling of the protective circuit to the amplifier.

Referring to Fig. 2, the schematic circuit illustrates an amplifier stage of the type wherein the amplifier tube operates, when properly excited from a source connected to its input circuit, in such manner that the negative bias for the grid electrode is derived solely from a voltage drop due to grid current flow in the grid circuit. Amplifiers of this type are generally known as non-linear amplifiers and may find application in transmitters or in industrial systems where linearity is not required for the intended operation of the amplifier. The source for supplying the input voltage to the input circuit of the tube is merely illustrated by means of a block diagram and is marked as the exciter. This may be a preceding amplifier or an oscillator, or any suitable source of voltage which the amplifier is called upon to amplify. Identical elements are designated with similar reference characters in both figures.

The input circuit of the tube 35 includes the grid 36, a grid resistor 11 and a grid current path between cathode and grid comprising in series the potentiometer 38 and the bias-source represented by the battery 13. One terminal of the latter and also the cathode 39 of the tube 35 are grounded. A low impedance path for the transmission currents supplied to the amplifier is obtained through the by-pass condenser 46, between the cathode 39 and the ground potential side of grid resistor 11. The exciter may be capacitively coupled to the input circuit through the coupling condenser 41.

The output circuit of the tube 35 includes the anode 42, the primary winding 43 of the output transformer 45 and the anode potential source shown by the battery 23. The primary winding 43 is also tuned to the transmission signal-frequency by means of the condenser 48. The output of the amplifier may be obtained for a utilization circuit not shown here from the secondary winding 47 of the transformer 45.

The protective circuit herein shown is capacitively coupled to the output of the amplifier by means of the condenser 48 which is connected to the cathode 49 of the rectifier tube 50 and to the anode 42 of the amplifier tube 35. The load resistance for the rectifier tube 50 is the potentiometer 38 which connects to the cathode 49, through conductor 51 and to the anode 52 of the rectifier 50, through conductor 53. The potentiometer 38 is also shunted by the capacitor 54. The variable arm 55 of the potentiometer 38 connects to the grid circuit resistor 37.

Considering the operation of the protective circuit for either oscillator or the amplifier it should be borne in mind that grid current flowing through the resistors 11 is the only means whereby a bias is developed on the grid electrodes of the tubes. Under normal operation, this bias is sufficient to prevent excessive current drain which at zero bias condition would seriously damage the vacuum tubes. The value of resistors 11 is so chosen that with proper excitation of the grid circuit, the grid current will be of sufficient magnitude to develop the required bias voltage across these resistors. In the oscillator, the excitation of the input circuit is obtained by feedback from the output circuit through the inherent grid-anode capacitance of the vacuum tubes. In the amplifier the excitation is provided from an outside source. Whatever may be the source of grid excitation, it is necessary that it should be maintained because failure thereof results in

damage of the tubes. In prior systems relays operating on grid current flow or on excessive anode current were utilized as protective means whereby upon condition of no excitation the plate voltage source was disconnected from the vacuum tubes. In the system in accordance with this invention, no mechanical switching devices are employed instead a fixed bias source is maintained in the input circuit ready at all times to supply a bias voltage of sufficient magnitude to prevent excessive current drain of the tubes should grid excitation cease for any reason at all. The battery 13 of Fig. 1 or of Fig. 2 is the source of the protective bias voltage. Under normal operation, there is no need for protective bias and as a matter of fact normal operation could not be obtained in the presence of such bias voltage. To eliminate the effect of the bias voltage under normal operation, a portion of the output circuit of the oscillator or the amplifier is utilized to furnish a voltage of such magnitude and in such polarity which will effectively counteract the fixed bias voltage, so that as far as the operation of the system is concerned, there is effectively no initial bias voltage present.

Assuming static conditions in the operation of the oscillator of Fig. 1, the oscillator may be started by short circuiting the terminals 15 and 16 with the switch 14, whereby the grids 4 and 7 will be at cathode potential. The change in plate current so obtained will start the oscillator into operation so that in the output circuit there appears a certain oscillatory energy which, in the form of a voltage at the frequency of oscillation determined by the tuned circuits appears also across the terminals of the tertiary winding 30 causing a current flow in the circuit including the rectifier 31, resistor 12 and condenser 32. The rectifier 31 is so connected in the circuit that the polarity of the voltage appearing across the resistor 12 is in opposition to the voltage supplied by the battery 13. When the voltage derived from the protective circuit, that is from the rectifier 31, across the resistor 12 is of the same magnitude as the voltage of the battery 13, the two voltages will cancel and effectively there is zero bias on the grids 4 and 7. At this point the grid current flowing in the input circuit of the oscillator between the grids 4 and 7, through the resistor 11 will be the sole means of providing a bias for the grids depending upon the value of the resistor 11 and the excitation voltage on the grid electrodes.

The value of the resistor 12 is so chosen that when the oscillator is operating at its rated output the rectified voltage of the tertiary winding 30 shall maintain therethrough a current of such magnitude which will produce a voltage substantially equal in magnitude to the voltage of the battery 13.

Similarly, in Fig. 2, the amplifier when properly excited will have an output voltage of sufficient magnitude which, when rectified by the diode 50 due to the capacitive coupling through the condenser 48, causes a unidirectional current flow in the potentiometer 38 of sufficient magnitude to cancel out the negative voltage of the battery 13 at the point where the arm of the potentiometer is set. It is to be noted here that in starting the amplifier in operation, there is no need for a short circuiting switch since excitation is not dependent upon operation of the tube inasmuch as it is furnished from a separate source. Assuming static condition of the amplifier, the value of the negative voltage supplied by the battery

13 is so chosen that it will not prevent operation of the tube as an amplifier, although it will prevent excessive plate current which may damage the tube. Consequently, when the exciter supplies voltage to the input circuit, the amplifier will operate at a lower value of amplification because of the bias voltage present. Whatever the amplification may be, a certain amount of voltage will be obtained across the potentiometer 38 which in proportion counteracts the bias of the battery 13. This also increases the amplification so that the voltage across the potentiometer 38 is progressively increased as amplification of the tube increases, until a point is reached when this voltage will be equal to the battery voltage or may even be higher. The sliding arm of the potentiometer, however, permits a regulation so that such portion of the potentiometer be selected where the two voltages cancel each other and there is zero effective bias on the grid 36. This is the normal operating condition at which time the operating bias is derived solely from grid current flow through the resistor 11.

It is evident from the above that if for any reason at all oscillation or amplification ceases, the counter-voltage becomes automatically zero, since it depends upon the operation of the system and the protective bias for the grid circuits is automatically applied from the battery 13.

I claim as my invention:

A protective system for oscillation circuits including, in combination, a pair of electron discharge devices containing anode, cathode and at least one grid electrode, respectively, an input circuit including said grid and cathode elec-

trodes, an output circuit including said anode and cathode electrodes, both said circuits being tunable to the frequency of oscillations, a resistance in said input circuit across which under normal operation a bias voltage is being developed due to grid current flow, a second resistance and a source of potential in series with said first resistance, said resistances and said source of potential forming a current path between grid electrodes and cathodes in said input circuit, a secondary circuit coupled to said output circuit including a rectifier and said second resistance, a condenser in parallel with said resistance whereby said rectifier produces a unidirectional voltage across said resistance, the elements of said secondary circuit being so proportioned that the voltage produced by said rectifier across said second resistance at normal oscillatory energy in said output circuit is substantially equal in magnitude to the voltage of said source, said rectifier being so connected in said secondary circuit that the voltage developed across said second resistance is of a polarity opposite to the polarity of said source in said input circuit whereby under normal operation the effect of said two voltages is substantially canceled and upon failure of operation in the absence of oscillatory energy the voltage of said source is the effective control potential in said input circuit, and means for initiating oscillatory current flow comprising switching means for momentarily short circuiting said grid-cathode path formed by said resistances and said source of potential.

HAMPTON JENNINGS DAILEY.
